(57) **CLAIM**

The ornamental design for a stapling motor, as shown and described.

DESCRIPTION

FIG. 1 is a perspective view of a stapling motor, showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof; and,

FIG. 8 is another perspective view thereof.

The dashed or broken lines shown in the drawings depict portions of the stapling motor, in which the design is embodied that form no part of the claimed design.
